UNITED STATES PATENT OFFICE

ROGER V. TERRY, OF HILTON VILLAGE, VIRGINIA, ASSIGNOR TO NEWPORT NEWS SHIPBUILDING AND DRY DOCK COMPANY, A CORPORATION OF VIRGINIA.

HYDRAULIC MACHINE

Application filed August 5, 1931. Serial No. 555,193.

This invention relates to hydraulic machines and particularly those of the type that may be used for the generation of power hydraulically or by applying power thereto. It may be used to cause a flow of water therefrom in the desired direction.

My invention relates more particularly to hydraulic power producing machines known as hydraulic turbines either of low or of high specific speed.

The principal object of my invention is to provide an hydraulic turbine in which the blades or vanes of the rotor or runner are pivoted and of variable angle with reference to a plane of rotation that is at right angles to the axis of the runner, the changes in the angles of the vanes being accomplished automatically by the flow of the water past or through the runner.

The accomplishment of the abovementioned object not only enables a turbine to operate at its maximum efficiency for varying loads but also allows the blades of the runner to accommodate themselves to changes in the hydraulic head or pressure of the source of supply of water and also to changes due to the angles of the wicket gates and the changes due to variations in the speed of rotation of the runner itself.

Automatically variable vanes when used as in my improved runner obviously eliminate complicated and expensive parts that have heretofore been required when changes in the angles of the vanes of a runner have been produced by adjustment of certain mechanism at or near the upper portion of the turbine shaft. Among the parts that are thus eliminated are governor pressure systems that can take care of the total capacity of the turbine, elaborate oil supply apparatus having rotating parts requiring stuffing boxes that require renewal from time to time and that are often the source of oil leaks as well as necessary pipes, parts and apparatus required to keep former adjustable vane runners in the best condition for efficient operation.

The rotor or runner hereafter to be described has many advantages not incident with former runners. In addition to auto-

matic operation at maximum efficiency, the runner vanes automatically open or are more inclined when starting a turbine, thereby giving a maximum starting torque with the use of a minimum flow of water. 55

The vanes also remain closed or at a minimum angle with the plane of rotation when the unit is being used as a synchronous condenser, resulting in a minimum loss of power when the runner is operating in either water or air. 60

Due to the cushioning action of a dashpot, to be described, foreign objects carried through the runner give much less trouble and greatly lessen the possibility of damage to the runner. 65

My improved runner, furthermore, can be readily installed in a turbine designed for use with a fixed blade runner. The substitution of my improved runner for a fixed blade runner does not require changes in the electric generator or the usual turbine governor. 70

It is well known in the turbine art that the angle at which water enters a runner varies with the angular position of the wicket gates, 75 and with the tangential speed of the runner. The angle of flow of the water entering the runner, with reference to the circular rotation of the runner, increases relative to a tangent to the circle of rotation, as the wicket gates are opened and decreased as the peripheral speed of the runner is increased. 80

It has been found from experiment that the center of pressure on vanes of the shape and angles of flow generally used for turbine runners, is located at a point about 30 to 35 per cent of the chord distance from the leading edge to the trailing edge of the vanes. It is the further object of this invention to pivot the vanes through or near their centers of pressure so that relatively small moments are required to turn them on their pivots while the runner is in operation. 85

It is deemed preferable to arrange the pivots of the vanes so that their axes will be 95 slightly upstream from their normal centers of pressure, so that they will tend to assume a position somewhat in line with the water flow entering the runner, in a manner similar to the action of the weather-vane. With the 100

vanes thus pivoted they will automatically tend to follow any changes in the angle of water entering the runner resulting from a change in gate opening or from a change in 5 head.

Figure 9 illustrates how the vanes are preferably pivoted with respect to the center of pressure on the vanes as found by experiment. The cross hatched portion represents 10 the development of a section through a vane along a flow line through the runner. P represents the center of pressure whose location varies somewhat with different flow conditions in the runner but which has been found 15 from experiment usually to be down-stream from a point 30 to 35 per cent of chord K-K. X represents the axis or pivot point of the vane. Y-Y represents a line through the center of pressure normal to chord 20 K-K. With the vanes freely pivoted as above described they will follow any changes of the water flow passing through the runner. Thus the action of the vanes is analogous to that of a correctly designed weather vane.

25 For a detailed description of several embodiments of my invention, which I at present deem preferable, reference may be had to the following description and to the accompanying drawings forming a part thereof in 30 which

Fig. 1 is a vertical sectional view of one form of a turbine embodying my invention.

Fig. 2 is a side elevation of the runner thereof.

35 Fig. 3 is a horizontal sectional view on the line 3-3 of Fig. 1.

Fig. 4 is a vertical sectional view on the line 4-4 of Fig. 3.

40 Fig. 5 is a vertical sectional view of a modified form of the runner.

Fig. 6 is a vertical sectional view on the line 6-6 of Fig. 5.

Fig. 7 is a vertical sectional view on the line 7-7 of Fig. 5.

45 Fig. 8 is a vertical sectional view of a modified form of the runner.

Fig. 9 is a cross sectional view of one of the runner vanes, indicating the relation of the center of water pressure to the longitudinal axis of its pivot.

50 In these figures, 1 is the scroll casing, 2 the wicket gates which are adjusted by the turbine governor in the customary manner, 3 the throat ring, 4 the draft tube, 5 the crown plate, and 6 the main bearing. The above parts, 1 to 6, are of standard design well known to the turbine art.

55 The numeral 7 represents the runner vanes which are pivoted in runner hub 8. 9 and 10 are roller bearings carrying the pivots of vane 7. Roller bearings 11 carry the centrifugal forces of the vanes set up by the rotation of the runner. Gear sector 12 is keyed to the vane stem and engages teeth on rack 13 which is bolted to dashpot piston 14 (Fig. 4).

Any desired number of runner vanes may be used. The piston 14 serves as a common connecting means between all vanes so that they will move together. The upper part of runner hub 8 is bored out to receive piston 14. 10 The depth of the bore may be made just sufficient to give the vanes the proper angular travel. The bottom of the bore and the runner cover 8' will then serve as stops to limit the angular travel of the vanes in either 15 direction.

10 It will be evident that the stroke of the dashpot plunger 14 may be made adjustable if desired. A cover plate 8' may be provided, or, as shown in Fig. 5, a flange 16' on the end 80 of hollow shaft 16 serves as a cover for the runner hub. Hollow shaft 16 connects the runner to an electric generator shaft (not shown) or other power transmitting device. In certain turbines, with vanes pivoted as 85 provided in this invention, sufficient weight can be embodied in the dashpot piston 14 to actuate the runner vanes in the desired manner.

100 It will be appreciated that the weight of the piston or plunger 14 together with its mechanical connections with the vanes of the runner constitutes a reactive device which may operate by itself to determine the operative angles of the vanes and such parts may 95 be supplemented by other parts, such as springs, hereinafter to be described.

105 The hub of the runner above and below piston 14 is filled with oil or other fluid medium. The dashpot piston 14 is provided with a hole or holes 19 of the correct area to 100 limit the rate of movement of the vanes resulting from a change in gate opening or a change in the hydraulic head acting on the turbine.

110 The hollow shaft 16 serves as a reservoir for reserve oil and, together with filling connection 17, serves as a means for supplying oil to the runner hub, as at 19'.

115 The lower part of the runner hub may also be filled with oil or packed with grease to lubricate the mechanism in the hub and to prevent water from entering around the vane stems. Packing 18, of rubber or other suitable material, helps to prevent water entering the hub and to prevent the loss of oil or grease around the vane stems.

120 Under certain conditions it is found desirable to connect vanes 7 to piston 14 by means of levers 26 and links 27 (Figs. 5, 6, 7 and 8) arranged so that the weight of piston 14 will produce a moment about the vane stems varying with the angular position of the vanes. It will be readily apparent that the levers 26 and links 27 may be designed in 125 a variety of different ways so as to give widely varying moments about the vane stems. Levers 26 are keyed to the vane stems 25 (Fig. 6). Links 27 are pin connected to the levers and to the dashpot piston 14'. Key 130

or keys 33 prevent piston 14 from rotating as a result of the torsional reaction from the links.

By use of connecting devices in the form of levers, as illustrated in Figs. 5-8 inclusive, the turning moment on the vanes produced by the piston 14' and the spring or springs varies according to the position of the piston, that is to say, when the piston is in its higher position with the spring under compression approaching its maximum the levers will be more nearly in alignment and the effective turning moment on the vanes will be low. As the piston descends the angles between the levers will be decreased and turning moment on the vanes will be consequently increased. This is contrary to the normal result of using directly connected compression springs whose reactive forces increase with compression.

The bottom of the runner hub is provided with a cap 20 held in place by bolt or bolts 21.

In cases where the weight of piston 14 is not sufficient to create the desired moments about the vane stems, a spring or springs 22 (Figs. 5 and 6) may be inserted between a stationary part and the piston or otherwise arranged to exert a force on the piston in the desired manner. In certain arrangements the spring force may be transmitted to the piston by a rod. In Fig. 8, 24 is a spring cap and 23 the spring acting on the piston 14'. Obviously in certain arrangements the spring cap may be omitted or may be made adjustable with reference to other parts.

Adjustable stops 32 (Figs. 6 and 7) may be employed if desired for limiting the angular movement of the vanes. Similarly the vanes may be locked in any fixed position, if desired.

It will be noted that no connection is provided between the runner vanes and any outside source of power for rotating them. The movement of the vanes is entirely automatic and regulated by the action of the water flowing past them, together with any moments resulting from the weight of the component parts of the mechanism connected to the vanes or resulting from the force of springs.

While the above description applies particularly to high specific speed runners of the so-called, propeller type where relatively few vanes are employed, the principle and means of actuating the vanes is applicable with modifications in design and construction to turbines of lower specific speed with a large number of vanes and to certain forms of centrifugal pump vanes or similarly constructed fluid pressure machines.

Since the vanes are pivoted as above described they will automatically tend to follow any changes in the angle of the water entering the runner produced by changes in the amount of opening of the wicket gates,

or by changes in the hydraulic head. The vanes being curved along the water flow lines so that the water is deflected in passing through the runner, as is customary in runner design, forces on the vanes are produced corresponding to the degree of water deflection. This deflection occurs at all times regardless of the position of the vanes with respect to the direction of flow of the water entering the runner.

To obtain maximum efficiency the vanes must, of course, have a definite position with respect to the water flow.

In general the maximum efficiency is obtained when the water enters the runner parallel to the vane at that particular part of the entrance edge, i. e., without impingement such as would create a shock loss, and when the water is discharged from the vane in such a manner that the absolute velocity will be parallel or nearly parallel with the turbine axis, i. e., without whirl loss at discharge.

It will be appreciated that there is a maximum efficiency position of the vane for each combination of flow conditions, consisting of the direction of water flow entering the runner, the velocity of this flow, and the tangential speed of the runner. With the vane at its proper angle to result in maximum efficiency under these particular conditions, all forces acting on each vane are equivalent to a single force acting through a center of pressure. This force multiplied by the distance from the axis of the vane to the center of pressure, creates a moment tending to rotate the vane about its axis. This moment is balanced by building into the runner hub a reactive device acting on the vanes through the proper mechanism. The moment required to hold the vanes in their proper position for the various conditions of flow are determined experimentally by calibrated springs properly connected to the vanes.

In the light of experimental data I am, of course, quite familiar with the action which takes place when the inlet flow angle is changed. This might perhaps be best illustrated by an example. Assume the runner to be in steady operation under certain flow conditions, the hydraulic moment on the vanes being balanced by a reactive moment provided by the mechanism in the hub. Now assume that the angle of flow relative to the runner is increased by increasing the wicket gate opening or angle or by decreasing the speed of the turbine. This is equivalent to increasing the "angle of attack", as generally known in aeronautics. The center of pressure moves down-stream an appreciable amount. The force on the vane is increased only slightly. The moment of the force about the vane axis tending to open the vane is increased directly in value or algebraically increased depending upon whether the center

130

of pressure was previously down-stream from the axis or up-stream from the axis. The hydraulic moment is greater than the reactive moment and a certain angular movement of the vane in the opening direction will take place. As the vane moves in the opening direction the angle of attack decreases, the center of pressure moves upstream, the hydraulic moment tending to open the vanes algebraically decreases until again balanced by the reactive moment. The vane movement then stops, at this balanced position, and the turbine operates with the vanes in the new position until the flow conditions are again changed. The above action takes place automatically.

From the above explanation it will be clear that the center of pressure is not fixed but varies somewhat with the flow conditions. It is really the change in the center of pressure which, together with the change in force on the vanes, causes the vane movement. Under normal conditions of operation at or near the best efficiency for the various flow conditions the center of pressure moves an appreciable amount but not a very large amount when compared with the chord distance. When starting up a runner from rest the water impinges directly on the vane at a very large angle of attack. Under this condition the center of pressure moves a relatively large distance down-stream towards 50 per cent of the chord distance as a limit. I find from experiments that this is a desirable feature as the vanes will open wide giving the required starting torque with a minimum quantity of water. As the runner picks up speed the angle of attack decreases, the center of pressure moves up-stream thereby reducing the hydraulic opening moment, and the vanes close until the hydraulic and reactive moments are balanced.

Similarly when the hydro-electric unit is used as a synchronous condenser, the runner being driven by the generator with the turbine gates closed, the angle of attack reaches a large negative value; the center of pressure moves down-stream a large amount; the vane force acts on the back side of the vane causing it to close, thus resulting in a minimum amount of power required to drive the runner in either water or air.

I find from experiments that within certain limits the vane may be pivoted with the center of pressure down-stream from its axis under all usual conditions of operation, it may be pivoted with the center of pressure up-stream from its axis, or it may be pivoted so that the center of pressure moves from one side of the axis to the other, when the flow conditions are varied. With the latter case no reactive moment is required when the vane force passes through the axis.

What I claim and desire to protect by Letters Patent is:

1. In an hydraulic machine, a runner, vanes pivoted therein on radial axes in a plane transverse to the shaft thereof and having the pivots thereof located to cause the axes thereof to lie above or up-stream with relation to the effective centers of water pressure on said vanes, yieldable devices within the runner hub which produce turning moments about said pivots whereby the flow of water past said vanes will permit their active surfaces to assume various angles relative to their plane of rotation, and connections between said parts to maintain said vanes substantially in definite lines with reference to the direction of water flow past said vanes for maximum efficiency. 70 75 80

2. In an hydraulic machine having a runner provided with longitudinally pivoted vanes, the improvement which comprises, connections between said vanes to cause them to move simultaneously about their axes, the pivots of said vanes being located to extend from points above the central longitudinal line thereof, whereby the effective centers of water pressure thereon will be produced at 90 points below or adjacent said axes and at varying distances therefrom in accordance with the changes in the angles of water flow relative to the plane of rotation of said vanes, and blancing means within the hub of said runner for placing and maintaining said vanes at the desired angle in accordance with the force and angle of water flow acting upon said runner. 95

3. In an hydraulic machine having a runner provided with pivoted vanes, the improvements which comprise, providing entirely within said runner, a counter-balancing device connected with said vanes, means acting thereon to cause a preponderance of pressure in one direction and operative to rotate said vanes upon their axes and to maintain a different angle thereof relative to their plane of revolution when the effective centers of pressures on the vanes are caused to move to other points relative to their axes of rotation. 100 105 110

4. In an hydraulic machine having a runner provided with longitudinally pivoted vanes, the improvement which comprises, providing entirely within said runner, connections between said vanes to cause them to move simultaneously about their axes, a balancing and reactive device connected with said vanes, said pivots being so positioned with reference to the body of said vanes that the axes thereof will lie above or adjacent the effective centers of water pressure on said vanes and at varying distances therefrom, said reactive device providing turning moments on said vanes which are decreasingly active with relation to said pivots in accordance with the increased distances between said axes and said centers of pressure. 115 120 125

5. In an hydraulic machine having a run-

6. In an hydraulic turbine having wicket gates for regulation of the water flow and a runner having pivoted vanes thereon, the improvement, which comprises, providing entirely within said runner, a weighted reactive device including a piston, a chamber enclosing said piston and fluid material in said chamber, constituting, with said piston, a dashpot, whereby said vanes are caused progressively and automatically to assume the proper angles and be maintained uniformly at such angles, for maximum efficiency, in accordance with the angles of water flow produced by said gates and the rates of water flow produced by the hydraulic head. 10
7. In an hydraulic turbine having wicket gates for regulation of the water flow and a runner having pivoted interconnected vanes thereon, the improvement which comprises, providing entirely within said runner, a reactive device including a piston, a chamber enclosing said piston and fluid material in said chamber, constituting, with said piston, a dashpot and a spring actuated device for exerting forces upon said piston in opposition to the forces produced by the water contacting with said vanes, whereby said vanes are caused progressively and automatically to assume the proper angles and be maintained uniformly at such angles, for maximum efficiency, in accordance with the angles of water flow produced by said gates and the rates of water flow produced by the hydraulic head. 15
8. In an hydraulic machine having a runner provided with pivoted vanes, the improvement which comprises, providing entirely within said runner, reactive devices connected with said vanes, said devices including a weighted plunger adapted to work in a chamber containing a fluid medium and constituting a dashpot, whereby said vanes are caused progressively and automatically to assume the proper angles for maximum efficiency in accordance with the required speeds of rotation and the angles and rates of water flow. 20
9. In an hydraulic machine having a runner provided with pivoted vanes, the improvement which comprises, providing entirely within said runner, reactive devices including a plunger adapted to work in a chamber containing a fluid medium, constituting a dashpot, and a spring active upon said plunger to effect the movement thereof in opposition to the forces produced by the water contacting with said vanes, whereby the latter are caused progressively and automatically to assume the proper angles for maximum efficiency, in accordance with the required speeds of rotation and the angles and rates of water flow. 25
10. In an hydraulic turbine having wicket gates for the regulation of the water flow and a runner having interconnected vanes pivoted in the hub thereof, the improvement which comprises, providing entirely within said runner, a dashpot having a piston that is connected with said vanes, means for determining the motion or stroke of said piston to limit the angular movements of said vanes, said piston being weighted and arranged to create a turning moment about the axes of said vanes and acting to oppose and more or less counterbalance the turning moments about said axes produced by the effective centers of pressure of the water flow contacting with said vanes, whereby said vanes assume positions with respect to the water flow such that the runner vanes will assume proper angle to develop the maximum efficiency under various conditions of load and hydraulic head for which the turbine is designed. 30
11. In an hydraulic turbine having wicket gates for the regulation of the water flow and a runner having vanes pivoted in the hub thereof the improvement which comprises, providing entirely within said runner, a dashpot having a piston that is connected with said vanes, means for determining the motion or stroke of said piston to limit the angular movements of said vanes, a spring within said hub and acting to supplement the force produced by said piston, said parts being adapted to affect turning moments about the axes of said vanes and acting to oppose and more or less counterbalance the turning moments about said axes produced by the effective centers of pressure of the water flow contacting with said vanes, whereby said vanes assume angles with respect to their plane of rotation such that the runner will develop the maximum efficiency under various conditions of load and hydraulic head for which the turbine is designed. 35
12. In an hydraulic turbine of the radial inflow and axial outflow type having wicket gates for regulation of the water flow and a runner having interconnected vanes freely pivoted in the hub thereof, the improvement which comprises, arranging the pivots of said vanes that their axes of rotation shall have definite relations to the centers of pressures on said vanes according to the angle of the water flow, the hydraulic head, and the de- 40

sired speed of rotation, a dashpot within said hub and having a counterbalanced piston for controlling and maintaining the angular positions of said vanes with respect to the angle of the water inflow, said runner being provided with means for determining the motion or stroke of said piston to limit the angular movements of said vanes about their respective axes, whereby the runner will develop the maximum efficiency under various conditions of load and hydraulic head for which the turbine is designed.

Signed this 3rd day of August, 1931.

ROGER V. TERRY.
